UPRIGHT EXTRUDING PRESS

Ferdinand Hanff, Berlin-Charlottenburg, Germany, assignor to Siemens-Schuckertwerke Aktiengesellschaft, Berlin-Siemensstadt, Germany, a corporation of Germany

Application June 20, 1932, Serial No. 618,212
In Germany June 27, 1931

8 Claims. (Cl. 207—9)

My invention relates to improvements in upright extruding presses.

In manufacturing lead tubes, particularly sheaths for lead covered cables, the recipient or cylinder containing the lead is filled up to its brim and often even beyond that, so that the lead rises in the form of a collar above the brim. In that collar and in the upper part of the cylinder, lead oxide, dross and other impurities collect.

For the removal of these impurities, it is known to provide the plunger with an edge by the means of which the plunger when entering the cylinder pushes away the impurities, for example sideways and upwardly, i. e. out of the cylinder top. This forcing aside of the top layers continues, until the plunger has penetrated with its full diameter into the cylinder and has closed it as a piston closes a cylinder. With the known arrangement, the edge of the plunger is obtuse, i. e. the surfaces forming the edge meet at an obtuse angle. That has the disadvantage that the distance travelled by the plunger on penetrating into the cylinder until it has completely closed the opening is but short. That distance is not long enough to remove all the impurities from the cylinder. Besides, the direction in which the impurities are pushed by the surfaces forming an obtuse angle is not so much upwardly as it is sideways towards the wall of the cylinder, with the result that some of the impurities are, after the cylinder has been completely closed by the plunger, driven forward by the latter. In this manner impurities still find their way into the product, for example into the lead sheath, and produce faults in the product which cause the known disturbances. With that method it is, therefore, not possible to remove the impurities completely.

According to the present invention, the above drawbacks are obviated by providing special expanded or outwardly flaring portions, or outlets for the passage of the material forced out of the cylinder on the application of pressure. There may be only a single recess, or there may be a plurality of such recesses. The recess can be provided in the cylinder as well as in or on the plunger or in or on both of these parts. The invention is applicable not only to new presses to be built, but also for improving existing presses. It also provides means for the easy removal of the lead collar forced out on the application of pressure. The details and advantages of the invention will be seen from the following examples for carrying out the invention, illustrated in the drawing in which:—

Figs. 1 and 1^a are vertical sections, showing more or less diagrammatically the upper part of a press cylinder provided with an expanded portion at its entrance, and showing in Fig. 1^a diagrammatically how the invention operates. 5

Figs. 2 and 2^a show in vertical section and plan view, respectively a practical construction of the expanded cylinder entrance according to the invention.

Figs. 3-7 show in vertical section several different forms in which the invention may be applied to the top of existing press cylinders, and

Fig. 8 shows in vertical section semi-diagrammatically the general arrangement of an entire press. 15

The invention can also be employed for other presses, for example presses for making lead tubes or sheaths and similar articles. The invention is not limited in its application to the illustrated examples, nor is the invention limited exactly to the particular construction illustrated in the various examples. Instead of the individual forms of expanded portions or recesses shown, for example slots and holes, other forms can be employed without thereby departing from the 25 spirit and scope of the invention.

Fig. 1 shows the upper end of the filled cylinder with the impurities floating on top before the entrance of the plunger, Fig. 1^a shows the moment the opening of the cylinder is being closed 30 by the head of the plunger. The numeral 2 indicates the cylinder, which is enlarged or widened in its upper part 3. 4 is the head of the plunger ending in a point formed by a cone 5 of small height. The material ejected from the cylinder 35 on the entrance of the plunger, and containing the impurities is indicated by 6 in Fig. 1^a. The axial length of the cylinder recess corresponds at least to the depth at which according to experience still an appreciable quantity of impurities are found. Such a dross cone is indicated at 7 in Fig. 1. 40

As will be seen from Fig. 1^a, the plunger 4 must penetrate fairly deep into the cylinder 2 and displace a corresponding quantity of lead 6 before closing the cylinder 2 tightly and thereby beginning the pressing operation proper. In this manner, the impurities are forced away sideways and upwardly. As far as they are pressed against the wall of the cylinder and cannot escape at the top, the impurities can only come up against the walls of the widened cylinder portion. They can, therefore, no more be taken along by the plunger, as soon as the latter has closed the whole opening of the cylinder. 50 55

- According to a practical form of the invention shown in Figs. 2, 2^a, the cylinder 32 has an outwardly flaring cone-shaped mouth 33 provided with radial ribs 34 extending to the contour line of the inner cylinder surface to form a guide for the plunger. Further, an annular trough 35 is arranged in the upper end of the cylinder wall into which the dross ejected through the interstitial spaces between the ribs overflows.
- 10 When the plunger 36 descends, the material in the upper cylinder portion on which float the oxide layers and the impurities is forced out of the cylinder through these interstitial spaces so that by the time the plunger has reached the
- 15 non-recessed cylinder wall, all impurities are ejected from the material. The advantage of employing these ribs is that the material forced out is at the same time subdivided, so that it can easily be removed from the top of the cylinder.
- 20 An advantageous manner of producing the funnel-shaped flare is to cut or grind out the material between the ribs 34. The ribs 34 can, however, also be fixed into the finished flare, for example by welding them onto the wall of the
- 25 flaring cylinder portion.

In the foregoing constructions, the cylinder is widened in its upper part, and the head of the plunger is provided with a conical pressing surface. Constructions of that kind are advantageous for new presses.

According to the invention, the same advantages can also be obtained with already existing presses in a very simple and inexpensive manner by placing a suitably flaring annular element on top of the cylinder. I am aware that top members on such cylinders are per se already known, but hitherto they have been used only as melting pots. For the purpose of removing the impurities, they have up to now not been employed. Through the invention it becomes now possible, as shown in Fig. 3, when the cylinder 41 and the annular top member 42 are filled with molten metal and the plunger 44 is introduced into the annular top member 42, for the plunger 44 to force out the molten metal 43 contained in the annular top member 42 and which includes the oxide layers and impurities on the surface of the metal between the plunger 44 and the inner wall of the top member 42. By this means, 50 impurities and oxides are prevented from getting into the cylinder proper, into the chamber of the press and so into the extruded tube.

In many cases it will also be advantageous to remove the impurities and layers of oxide by using a top ring 52 (Fig. 4) provided with one or more closable outlets 53, through which the metal 54 contained in the ring together with the oxides and impurities floating on its surface can flow off.

60 The freeing of the lead from the oxides and impurities can be still more effectively performed, if, when filling the cylinder 61, the molten lead is allowed to flow over the top ring 62 for some time (Fig. 5). In that case it is of advantage 65 to provide the top ring 62 with an outlet spout 63 having preferably a slanting position and through which the lead 64 is discharged. When filling the cylinder 61, it is expedient to introduce the plunger 65 so far into the top ring that the pressing surface 67 of the plunger is in contact with the molten lead 64, so that this surface is heated by the molten lead. The pressing surface is thereby prevented from coming again into contact with the air, and consequently no oxides can 70 form.

It has also proven useful, as shown in Fig. 6, to place into the annular top member 71, formed in the same or a similar manner as the top member 62 of Fig. 5, a cone-shaped insertable member 72, for example in the shape of a funnel, 5 sufficiently far so that it dips into the lead. Through this member, the flowing-off of the oxides of lead to the overflow channel 74 is facilitated.

The employment of the top member has the 10 advantage that the cylinder consisting of high quality, especially hard material need not be machined, so that a saving in costs is obtained and the useful length of the cylinder is not lessened. The arrangement according to the invention has, 15 besides, the particular advantage that it can be readily fitted to already existing presses, whereby the occurrence of faults in lead sheaths is easily and reliably avoided.

A further improvement of the arrangement according to the invention is illustrated by Fig. 7. In this arrangement the invention proposes to provide the annular top member 83 bolted to the cylinder wall, and having the funnel-shaped bore of Fig. 3, and forming the extension of the cylinder chamber 82, also with a trough 86 surrounding the bore for receiving the metal forced or flushed out of the cylinder top. The molten lead is thereby prevented from flowing over the wall of the cylinder and soiling the press. It is thus 30 possible to remove without difficulty the lead plates forming in the trough, particularly if the trough is subdivided by ribs 84 into several compartments, so that separate plates of relatively light weight are formed. It is advantageous to 35 project a certain distance above the edges of the trough, because the lead in the different compartments is thereby prevented from flowing together and forming a circular ring, when the compartments are full. In some cases it may be of 40 advantage to design the ribs so that, as shown in Fig. 7, most of the ribs 84 protrude beyond the trough edges, while a small number has a height lower than the trough. This has the advantage that the uniform filling of the trough compartments is speeded up by those, more rapidly filling, overflowing into the others which fill less rapidly. As a ring, which solidifies, also forms between the plunger of the press and the trough, and as the removal of that ring from the plunger makes it 50 necessary to subdivide the ring, it is of advantage to extend all, or at least some of the ribs 84 inwardly to points in alignment with the surface of the cylinder bore. The cast ring is, thereby, completely subdivided into a number of segments 55 which can be easily removed. To facilitate still more the removal of the ring segments from the trough, it is advisable to provide the trough with outwardly slanting walls and the trough bottom with an outwardly rising slant, so that the individual plates can be lifted out by means of a chisel-like tool. Instead of placing a separate trough-like top member on the top of the cylinder, it is under certain conditions also possible, particularly when building new presses, to design 60 the top member of the above-described shape as an integral part of the cylinder.

A lead press for making sheaths for cables with a receiver according to the invention is shown diagrammatically in Fig. 8 in vertical section. 70 On the base 150 containing the horizontally directed die 151 through which the metal is ejected, is mounted the vertical cylinder 152 containing the space 153 filled with metal. The plunger of the press is indicated by 154. It is pressed in the 75

irection shown by the arrow 155. Hereby the lead sheath covering the cable is made in the known manner. The cylinder is provided at the top with an expanded portion 156, from which the lead containing the dross is expelled in the shape of a collar 157 as soon as the plunger enters this portion, assuming, of course, that this portion was initially filled to the top.

I claim:—

1. An extruding press for producing tubular lead sheaths or the like of lead or similar plastic materials, having an upright cylinder to be filled with liquid lead to be extruded and a piston tightly fitted into said cylinder for expelling the metal at the lower end thereof, said cylinder having an extension traversed by the piston on its extrusion stroke, and being located at the upper cylinder end and tapering toward said cylinder and forming a container for holding an excess amount of metal to be supplied when filling the cylinder, so as to permit the contents in said extension to form a lost head for the cylinder metal, containing the dross and being displaceable from said extension in liquid state when the piston passes through said extension into the metal contained in said cylinder.

2. An extruding press for producing tubular lead sheaths or the like, having an upright cylinder to be filled with liquid lead to be extruded and a piston tightly fitted into said cylinder for expelling the metal at the lower end thereof, said cylinder having an expanded upward extension traversed by said piston, and tapering outwardly from said cylinder for holding an excess amount of lead to be supplied when filling the cylinder, so as to permit the contents in said extension to form a lost head, containing the dross and being displaceable from said extension in liquid state when the piston passes through said extension into the metal contained in said cylinder.

3. An extruding press for producing tubular lead sheaths or the like, having an upright cylinder to be filled with liquid lead to be extruded and a cone-shaped piston tightly fitted into said cylinder for expelling the metal at the lower end thereof, said cylinder having an expanded upward extension traversed by said piston, and tapering outwardly from said cylinder for holding an excess amount of lead to be supplied when filling the cylinder, so as to permit the contents in said extension to form a lost head, containing the dross and being displaceable from said extension in liquid state when the piston passes through said extension into the metal contained in said cylinder.

4. An extruding press for producing tubular lead sheaths or the like, having an upright cylinder to be filled with liquid lead to be extruded and a piston tightly fitted into said cylinder for expelling the metal at the lower end thereof, said cylinder having an expanded upward extension traversed by said piston, and tapering outwardly from said cylinder for holding an excess amount of lead to be supplied when filling the cylinder, so as to permit the contents in said extension to form a lost head, containing the dross and being displaceable from said extension in liquid state when the piston passes through said extension into the metal contained in said cylinder, and means for receiving the contents displaced from said expanded portion to prevent its return to the cylinder after the piston has passed through said extension.

5. An extruding press for producing tubular

lead sheaths or the like, having an upright cylinder to be filled with liquid lead to be extruded and a piston tightly fitted into said cylinder for expelling the metal at the lower end thereof, said cylinder having an expanded upward extension 5 traversed by said piston, and tapering outwardly from said cylinder for holding an excess amount of lead to be supplied when filling the cylinder, so as to permit the contents in said extension to form a lost head, containing the dross and being displaceable from said extension in liquid state when the piston passes through said extension into the metal contained in said cylinder, and an overflow trough having outwardly flaring walls and surrounding said extension to receive the material 10 displaced from said extension to prevent its return to the cylinder.

6. An extruding press for producing tubular lead sheaths or the like, having an upright cylinder to be filled with liquid lead to be extruded 20 and a piston tightly fitted into said cylinder for expelling the metal at the lower end thereof, said cylinder having a ring mounted at its upper end and forming an expanded upward extension traversed by said piston and tapering outwardly from 25 said cylinder for holding an excess amount of lead to be supplied when filling the cylinder, so as to permit the contents in said extension to form a lost head, containing the dross and being displaceable from said extension in liquid state 30 when the piston passes through said extension into the metal contained in said cylinder.

7. An extruding press for producing tubular lead sheaths or the like, having an upright cylinder to be filled with liquid lead to be extruded 35 and a piston tightly fitted into said cylinder for expelling the metal at the lower end thereof, said cylinder having a ring mounted at its upper end and forming an expanded upward extension traversed by said piston and tapering outwardly from 40 said cylinder for holding an excess amount of lead to be supplied when filling the cylinder, so as to permit the contents in said extension to form a lost head, containing the dross and being displaceable from said extension in liquid state when 45 the piston passes through said extension into the metal contained in said cylinder, and an overflow trough surrounding said expanded cylinder extension and having outwardly flaring outer walls higher than the ring portion forming said cylinder 50 extension, for receiving the material displaced from said extension to prevent its return to the cylinder.

8. An extruding press for producing tubular lead sheaths or the like, having an upright cylinder to be filled with liquid lead to be extruded 55 and a piston tightly fitted into said cylinder for expelling the metal at the lower end thereof, said cylinder having an expanded upward extension traversed by said piston and tapering outwardly 60 from said cylinder for holding an excess amount of lead to be supplied in filling the cylinder, so as to permit the contents in said extension to form a lost head, containing the dross and being displaceable from said extension in liquid state when 65 the piston passes through said extension into the metal contained in said cylinder, said piston having a removable cone-shaped head and being tightly fitted into said cylinder for expelling the metal at the lower end thereof, and an overflow 70 trough having outwardly flaring walls and surrounding said extension to receive the material displaced from said extension to prevent its return to the cylinder. 75
